UNITED STATES PATENT OFFICE.

ARTHUR LIPSCHUTZ, OF CHICAGO, ILLINOIS.

CAR-TRUCK SIDE FRAME.

No. 883,143.

Specification of Letters Patent. Patented March 24, 1908.

Original application filed October 22, 1906. Serial No. 340,019. Divided and this application filed December 10, 1906. Serial No. 347,089.

To all whom it may concern:

Be it known that I, ARTHUR LIPSCHUTZ, a citizen of the United States, and a resident of Chicago, county of Cook, and State of Illinois, have invented a certain new, useful, and Improved Car-Truck Side Frame, of which the following is a full, clear, and exact description, such as will enable others skilled in the art to which it appertains to make and use the same.

My invention relates to railway car-trucks and has special reference to improvements in trucks of that class wherein the journal boxes are rigidly secured in the truck side-frames, and wherein the truck bolster is supported by springs in or upon said side-frames. In a truck of this class the truck bolster is usually of about the same length as the car axles, and its ends extend through or beyond the side frames, the bolster springs being arranged in the vertical planes of the side-frames.

The object of my invention is to improve the construction of the side-frames of car-trucks of the class mentioned, and the particular object of the invention is to provide an improved cast-steel side frame for car-trucks.

Further and particular objects of the invention are to provide single-member cast-steel side-frames of such character that the bolster may be inserted into the openings of said frames after the frames and journal boxes have been placed upon the truck wheels; further, to provide an improved single-member side frame which shall be characterized as above and which nevertheless, shall have continuous or uninterrupted top and bottom chordal portions or flanges.

Other objects of my invention will appear hereinafter.

My invention resides in a novel cast metal side frame for car trucks of the construction hereinafter described and particularly pointed out in the claim.

My invention will be more readily understood upon reference to the accompanying drawings, forming a part of this specification, and in which

Figure 1 is a side elevation of a railway car truck, provided with a side frame embodying my invention; Fig. 2 is a partial plan view thereof; Fig. 3 is an enlarged inner side view of my novel side frame; Fig. 4 is a vertical section on the lines X-X of

Figs. 1, 2 and 3; and Fig. 5 is a perspective inner side view of the side frame.

As shown in the drawings, 2-2 represent the wheels of a car-truck; 3-3 the axles; 4-4 the journal boxes; 5 the bolster; 5' the bolster guides, secured upon the bolster; 6-6 the bolster springs, and 7, a bottom tie-bar. The parts of the car truck here mentioned may be of any suitable form or construction adapted for employment with rigid side-frames. My novel side frame comprises a single steel-casting, A, having ends, B, that are secured upon the tops of the journal boxes by the usual bolts, which latter also secure the ends of the tie bar, 7.

My side frame is a single piece of metal, being preferably a steel casting. The middle portion of the side frame or beam is provided with a bolster and spring opening, gap or pocket, C. The bottom and top flanges or chordal portions, D and E, are continuous, extending from end to end of the beam, but the top portion, E, is curved outwardly adjacent to the opening, C, thereby providing space for the admission of the bolster, 5, from above, as is well shown, in Figs. 2, 4 and 5. The outwardly curved portion, E', of the top flange, E, affords the requisite strength in the upper part of the side frame, without closing the top of the frame. The gap between the main portions of the frame is closed by a light locking bar, F, secured to the top flange by bolts, F'. This bar serves to hold the bolster in place after the spring and bolsters are assembled in the frame. The lower flange, D, of the frame is widened or expanded at the middle to form a spring seat portion, D'. Upon the outer side of the beam, this spring seat is joined to the top flange, E', by a vertical web or wall, A'', integral also with the web portions, A', of the beam or frame.

On the inner side of the beam, a like wall, A''', rises to a point somewhat beneath the normal position of the bolster and there terminates in a horizontal flange, E''.

It will be noted that the spring seat portion, D', the high outer wall, A'', and the low inner side wall, A''', form a complete pocket for the springs and the end of the bolster. The end portions of the pocket contain the bolster columns, G-G, which are integral with adjoining portions of the frame. These interlock with the guides, 5', on the bolster and serve to guide the bolster vertically and to prevent end-wise motion thereof. A suf-

ficient gap or space, H, is provided between the end of the bolster and the inner side of the wall, A'', it being desirable to prevent the engagement of the bolster with the 5 side of the frame, the columns being adequate as guides for the bolster. It will be observed that the locking bar extends between the tops of the columns and when in position practically completes the top flange, 10 E, of the frame. I find it preferable to place the walls, A'' and A''' at substantially equal distances from the middle vertical plane of the frame, but it will be obvious that the 15 spring pocket may be non-symmetrical with reference to the web or middle plane of the side frame. This and other modifications of my invention will readily suggest themselves to one skilled in the art and I do not confine the invention to the specific structure 20 herein described.

In assembling my novel railway car truck, the journal boxes are rigidly secured to the side frames and are placed upon the axles; the side frames are then tied and braced by 25 suitable members (not shown) of ordinary design, after which the truck is ready to receive the bolster, 5. The spring being placed in position, the bolster is next lowered into

the spaces or openings in the side-frames and properly engaged with the guides or columns 30 thereof. The locking bars are then bolted upon the frames to secure the bolster therein.

Having thus described my invention, I claim as new and desire to secure by Letters Patent:

The herein described improvements in car trucks, comprising a single member side frame having continuous top and bottom chordal portions, said top chordal portion being bowed outwardly at the middle to admit a bolster, a vertical plate portion extending between said chordal portions and at the middle substantially conforming to the bowed out part of the top chordal portion and an inwardly bowed vertical plate portion 45 of less height than the main plate portion, a spring pocket being formed between the inwardly and outwardly bowed portions, substantially as described.

In testimony whereof, I have hereunto set 50 my hand, this 8th day of December, 1906, in the presence of two subscribing witnesses.

ARTHUR LIPSCHUTZ.

Witnesses;

CHARLES GILBERT HAWLEY,
F. G. KNIGHT.
